BATTERY BOX AND PROCESS OF MAKING
THE SAMELouis W. Hottel, Los Angeles, Calif., assignor to
The Richardson Company, Lockland, Cincinnati,
Ohio, a corporation of OhioApplication July 26, 1932, Serial No. 624,785
Renewed October 12, 1935

9 Claims. (Cl. 136—166)

The invention concerns a battery box formed by pressure as distinguished from a box formed by vulcanization, and in which a so-called cold press composition is used such as will set to final form by allowing it to cool in the press in which the molding operation is performed under heat. Invention also resides in the process involved in making the box.

The box is formed by molding the box body and uniting therewith a pre-formed partition, or partitions, which is blended or welded integrally with the material of the box body during the molding of the latter, the union being due to the pressure exerted during this molding operation in the presence of heat and the subsequent cooling of the molded-together material while still in the press.

The invention is illustrated in the accompanying drawing showing in perspective a battery box. In this drawing, 1 indicates a pre-formed partition, 2 the box body molded into integral connection with the partition or partitions, the arrows A indicate the general direction in which the grain of the partition runs, and the arrows B indicate the general direction in which the grain of the box body runs.

In carrying out the process, the partitions are formed first, i. e., independently of the molding operation which produces the body of the box. The material or composition of which the partitions are formed may be entirely different from the composition or material of which the body portion of the box is composed. This material from which the partitions are made is first sheeted out or calendered to the proper thickness and then the sheets are cut to provide the partitions of the desired size. These partitions are placed on a warming plate and subjected to a temperature which will aid in conditioning the material of the partitions properly for their union with the body portion of the box, when the latter is molded with the partitions set in the molding apparatus in proper relation to assume the prescribed relation to the walls of the box when molded.

The warming plate keeps the material of the partition in soft condition suitable for molding the body of the box into connection therewith.

This temperature will vary according to the composition used for the body of the box. As one instance of a suitable temperature, 270° F. may be mentioned. The slabs forming the partitions are inserted in recesses or openings in the mandrel or core of the molding apparatus and these recesses or openings may be those which, in mold-

ing operations as heretofore practiced, receive the material from the biscuit or mass of moldable material during the molding operation which in said known practice forms the box and the partitions from the same operation and from the same batch of materials.

Having placed the substantially pre-formed and pre-heated partitions in the recesses between the sections of the mandrel or core, and having placed the biscuit or mass of moldable material intended to form the box body on top of the mandrel or core, the press is closed so that the core or mandrel carrying the substantially pre-formed partitions and the biscuit of body material enters the mold body and the molding operation takes place. In performing the molding operation, apparatus may be used such as is disclosed in application for Letters Patent of the United States, filed February 9, 1932, Serial No. 591,900, though the invention is not limited in its manufacture or performance to any particular apparatus. In this molding operation, pressure is immediately exerted upon the body material which therefore fills the recesses within the mold intended to shape and dimension the body of the box. This pressure is also transmitted to and throughout the material comprising the partitions which, being in comparatively soft condition, will be compacted or compressed so that it will conform to the shape of the recess in which said preformed partition was positioned prior to the beginning of the molding operation.

In other words, the pressure due to the molding operation is transmitted through the body material to the edge portion of the substantially pre-shaped, soft material of the slab and throughout the depth of the slab. This pressure, together with the soft condition of the substantially pre-shaped slab for forming the partition, causes the material of the slab to flow sufficiently to acquire its final shape and to effect a firm union with the material which is in the act of being molded into the form of the complete box.

The slab in the molding operation is preferably somewhat more rigid than the material of the body of the box.

In performing the molding operation in connection with an apparatus such, for instance, as that disclosed in my application above referred to, the core carrying the substantially pre-formed partition slab and the heated mass of body forming material on its top is moved up into the mold and heat is delivered to the sections of the mandrel or core. The degree of heat will be, say, about 130° F. This temperature will

vary according to the stiffness or rigidity of the materials forming the composition of the body of the box. Hot and cold water may be used to heat and cool the mandrel or core such as is disclosed in my application before mentioned. The hot water for heating the core may be of such a temperature and have such a rate of flow as to heat the core to a temperature of about 115° to 212° F. (varying with the character of the compound) within one minute. The proper molding temperature is maintained for approximately 15 seconds after the press is completely closed until displacement of the hot water takes place, at which time the cooling system begins the reduction in temperature of the core or mandrel.

15 The material from which the body of the box is molded may be of a temperature of from 250° F. to 300° F. when it is placed on top of the core or mandrel.

20 After the press has been closed for about 15 seconds, a reduction of the temperature on the core starts and continues for from 2 to 5 minutes at which time the molding cycle is completed. The core with the completely molded article is 25 now lowered from the die box and the molded box with the partitions united homogeneously therewith is removed. When the core is about midway of its downward stroke the cold water is turned off and the hot water is turned on to 30 heat the core. The die box may be heated by circulating hot water so as to maintain it at a temperature of about 110° to 130° F.

35 The partitions of that type of battery box which is made in one piece by well known processes involving a molding operation are the weakest parts of the box. This is due to the fact that in molding the partitions at the same time that the body portion of the box is molded the grain of the partition runs in the direction of the line of 40 pressure, and hence perpendicularly to the plane of the bottom of the box so that when lateral pressure of a certain degree is brought to bear on the partition it will crack along a line coinciding with the grain.

45 In my method, however, in which the material of the partition is first sheeted by calendering, and then the sheeted material is cut to the proper size and shape for forming the partition, the completed slab is so positioned that it will have 50 its grain running substantially parallel with the plane of the bottom of the box or, in other words, the grain of the partition will run in a direction at right angles to the grain of the box body or from side to side of the box instead of from top 55 to bottom of the box. Lateral strains imposed on such a partition will be at right angles to or across the lengthwise direction of the grain, and hence the partition will flex laterally without breaking, and thus a stronger and more durable 60 partition will be produced than by the usual method of molding the partition simultaneously with the body of the box.

Furthermore, such a pre-formed molded-union partition will be free from flow lines. A flow line 65 may be described as the line where the material flowing from opposite directions meet during the molding operation. Such flow lines are lines of weakness in the partition where breakages occur under stresses imposed laterally of the partitions. 70 In a partition which is pre-formed by first sheeting or calendering the material, such flow lines do not exist. It may be pointed out further that with a pre-formed, "set-in" partition, into connection with which the body portion is united

during the molding of the latter, the pressure applied during the molding operation will be transmitted to the soft material of the set-in partition and in a direction transverse to the direction of its grain, but in the plane of the sheet or slab so that a compacting effect upon the grain will be exerted rather than a disrupting effect, it being borne in mind, as above mentioned, that the partition is set in the recesses of the mandrel or core with the grain thereof running from side to side of the mandrel substantially parallel with its top face instead of perpendicular thereto. By my invention a strong, laterally flexible partition is provided, and one free from both flow lines and pores, the latter being eliminated by reason of the compacting influence of the pressure transmitted during the molding operation to the soft material of the slab or sheet which finally forms the partition, said pressure being exerted in the direction of the 20 plane of said slab.

25 The partition forming material may vary in constituents. I give the following as one example: Gilsonite 30%; asphalt 6%; cotton 16.5%; rubber 13.5%; sulphur 2.42%; talc 31.58%. To a batch of 300 lbs. of this composition is added 1½ lbs. of stearic acid. The material according 30 to the above formula will have the quality of flowing under pressure, and will be sheeted as above described by passing it through calender 35 rolls.

The box body material may be composed of 40 bitumen, fibrous binder, and an acid resistant filler, this composition being well known. As the partition is formed separately from the box body the material thereof may be any desired composition which will give the characteristics of acid resistance, strength, flexibility, and capacity to unite with the box body material during the molding of the latter by a homogeneous flux or 45 blending action.

The following advantages may be enumerated as flowing from my invention:

50 The material of the partition may be of different character from that of the box body, that is to say, either a composition of a different character from that of the box body may be used, or a material entirely foreign to a composition may be used.

A rubber composition may be used for the 55 partition having a sufficient percentage of bitumen to unite with the so-called asphalt or bitumen composition of which the box body may be formed.

The partition may be set with its grain running 60 parallel to the bottom of the box as shown at A in the figure, thus increasing its strength to resist tendency to snap apart either during the molding operation or in use. B in the figure represents the general direction of grain of the box body.

65 Flow lines are eliminated due to the pre-forming of the partitions by sheeting or calendering, said flow lines being due to the meeting of the materials flowing from different directions during ordinary molding operation.

Porous spots throughout the partitions are 70 eliminated and particularly at the top edge of the partition. These porous spots are due in the ordinary molding operation to the comparative slow rate of flow of the stock into the recesses of the core or mandrel which causes that portion of the stock to chill and become stiff resulting in the formation of voids in the material.

75 My invention also permits the use of higher temperatures on the core without detrimentally

affecting the molding of the partitions, the result being a highly finished inner side of the box having the capacity to increase the acid resistance of the material.

5. A comparatively cheap grade of material for the box body may be used with a higher grade of material for the partition, this last mentioned part of the box being that where most of the trouble occurs.
10. The material of the partition may have a higher acid resistance than the material of the body of the box.

I claim:

1. The herein-described method of making battery boxes comprising bringing together a heated mass of body forming material and a heated, pre-formed slab of material to serve as a partition and with said slab in such relation to the mass as will determine the position of the partition in the completed box, and subjecting the materials to molding pressure while under heat to thereby weld or blend the box body material with the slab during the molding of said box body, and allowing the welded materials to cool, substantially as described.
2. The method comprising making battery box partitions, inserting said partitions between the core sections of a mandrel, applying the battery box material on top of the mandrel and inserting the mandrel with the said box forming material and partitions into the mold, and integrally uniting the body material and the partition under heat, pressure, and subsequent cooling.

3. A process according to claim 1 in which the partition is placed initially in relation to the mass with its grain running in a direction at right angles to the line of pressure to which the materials are subjected during the molding action.

4. A method of making battery boxes, comprising supporting pre-formed bitumen-containing material to serve as partition means, and molding under pressure unmolded bituminous plastic material into adhering contact with the said partition means, thereby forming the box body from the said unmolded material and integrally unit-

ing the box body material with the said partition means during the molding of the box body.

5. A method of making battery boxes, comprising supporting pre-formed bitumen-containing material to serve as partition means, and molding under pressure unmolded bituminous plastic material into adhering contact with the said partition means while the temperature of the said unmolded material is raised, thereby forming the box body from the said unmolded material and integrally uniting the box body material with the partition means during the molding of the box body.

6. An unvulcanized battery box comprising a preformed partition, and a box body molded, from unformed material, into connection with the said preformed partition, the said box body and pre-formed partition being made of material containing asphaltic matter.

7. A battery box comprising an unvulcanized box body and preformed partition means integral with the said box body, the said partition means having a grain running in a direction substantially parallel with the bottom of the box, and having a different composition from the composition of the box body, and said partition being free from meeting or flow lines and of higher acid resistance than the box body.

8. An unvulcanized battery box comprising pre-formed partition means made of a composition containing bituminous matter and fibers, and a box body molded into connection with the said preformed partition means from unformed material also containing bituminous matter and fibers.

9. In a battery box having its box body molded from material containing bituminous matter, filler, and fibers, and separately formed partition means integrally connected at the edges to the interior wall of the box also made of material containing bituminous matter, filler, and fibers, the general direction of the fibers in the sides of the box being at an angle to the direction of the fibers in the partition.

LOUIS W. HOTTEL.
